United States Patent Office.

THOMAS E. MARABLE, OF PETERSBURG, VIRGINIA.

Letters Patent No. 85,017, dated December 15, 1868.

TOY-PISTOL.

The Schedule referred to in these Letters Patent and making part of the same.

To all whom it may concern:

Be it known that I, THOMAS E. MARABLE, of Petersburg, in the county of Dinwiddie, and State of Virginia, have invented a new and improved Toy-Pistol; and I do hereby declare that the following is a full, clear, and exact description of the construction and operation of the same, reference being had to the accompanying drawings, making a part of this specification, in which—

Figure 1 is a perspective view.

Figure 2 is a longitudinal vertical section.

This invention relates to that class of toy-guns and pistols in which the projectile is forced from the barrel by means of an elastic cord; and

It consists in providing an adjustable stop, which will prevent the ball from accidentally falling out of the barrel, although not interfering with the operation of the toy when the cord, having been drawn back over the notch, is disengaged therefrom by the trigger.

In the drawings—

A is the barrel, provided with a tubular bore, *a*, and a transverse slot, *b*.

B is the stock.

C is the elastic cord, on each side of the barrel, attached to the latter at *c*.

E is a short piece of metal, wood, or other suitable material, attached, at its ends, to the loose ends of the two cords C C, and extending through the slot *b*.

e is a notch, at the breech of the bore, and in its lower surface, fitted to receive and hold the short bar E, in the manner clearly shown in fig. 1; and

D is the trigger, adjusted so that, when pulled, as in an ordinary gun, it disengages the bar E from the notch *e*, and allows the cords C C to throw the bar forward, with sudden and great violence, to the forward end of the slot *b*, thereby forcing from the barrel and hurling to a considerable distance whatever projectile may have been placed therein.

In connection with these parts, arranged and operating as above described and shown, I cut a vertical slot, *m*, in the upper side of the barrel; and at the point *n*; I fasten to the barrel a piece, N, of tin or other suitable material, bent down into the barrel through the slot *m*, as seen in the drawings, and thence extending upward and backward, as seen at *n'*.

To accommodate the metallic piece N to its situation and purposes, it is made wider at the ends than in the slot, as seen in fig. 1.

The object of this piece is to hold the projectile in position, and prevent it from dropping from the barrel when the muzzle is lowered. To this end, it is so constructed that it will slightly project into the barrel in front of the ball, as seen in fig. 2, in which *o* represents the projectile, and thereby will prevent the weight of the latter from causing it to fall out, under any circumstances; but the rigidity of the spring is so small that, when the elastic cords are sprung, they will, with perfect ease, overcome its resistance, and carry the projectile forward, as above described.

If the spring N is made of soft tinned iron, or other suitable material, it can be regulated at pleasure, it being only necessary to bend it down into the slot more or less, which can be readily done by the pressure of the finger, or by pushing its rear end forward, so as to double it at the centre, or drawing it back, so as to straighten it.

I do not confine myself to any particular construction of the gun-barrel, or to the materials of which the toy is made, although I would ordinarily make the barrel of some sheet-metal, and the stock of the same, or of wood.

Having thus described my invention,

What I claim as new, and desire to secure by Letters Patent, is—

1. The spring N, when employed in a toy-pistol or gun, substantially as and for the purpose described.
2. As an article of manufacture, a toy-gun or pistol, having a barrel, A, slotted at *b* *m*, a stock, B, a trigger, D, elastic cords C C, connected with a short rod, E, operating in the slot *b*, and a spring, N, operating in the slot *m*, the whole being constructed to operate substantially as and for the purposes specified.

To the above specification of my invention, I have signed my hand, this 27th day of October, 1868.

T. E. MARABLE.
